UNITED STATES PATENT OFFICE.

LOUIS SANDERS, OF BROOKLYN, NEW YORK.

DESIGN FOR A BELT-BUCKLE.

SPECIFICATION forming part of Design No. 19,359, dated October 15, 1889.

Application filed September 11, 1889. Serial No. 323,654. Term of patent 3½ years.

To all whom it may concern:

Be it known that I, LOUIS SANDERS, of the city of Brooklyn, in the county of Kings and State of New York, have invented and produced a new and original Design for Belt-Buckles, of which the following is a specification, reference being had to the accompanying drawing, forming a part thereof.

The figure of the drawing represents a front elevation of my design.

The design consists of the representation of two link-like figures A, two crossed anchor-like figures B, interposed between the link-

like figures, and button-like figures C, appearing upon the central meeting lines of 15 the anchor-like figures.

I claim—

In the design for a belt-buckle herein shown and described, two link-like side figures and two interposed crossed anchor-like 20 figures, as specified.

LOUIS SANDERS.
